MARCUS B. BEHRMAN, OF NEW YORK, N. Y., ASSIGNOR TO THE LOX SEAL CORPORATION, OF BROOKLYN, NEW YORK, A CORPORATION OF NEW YORK.

LOCK-TAG.

1,397,917.

Specification of Letters Patent.

Patented Nov. 22, 1921.

Application filed March 23, 1920. Serial No. 368,000.

To all whom it may concern:

Be it known that I, MARCUS B. BEHRMAN, a citizen of the United States, and a resident of New York, in the county of New York and State of New York, have invented certain new and useful Improvements in Lock-Tags, of which the following is a specification.

The invention relates to means for correcting, so far as may be possible, the too common practice of certain persons having garments sent home from a store on approval and after wearing the garments, returning the same to the store for credit or exchange. It has been discovered that some persons have had garments sent home on approval without any intention of purchasing the same and that after wearing the garments for some occasion, have returned the same to the store.

My invention provides an identifying tag to be conspicuously borne by garments or the like, including hats, showing that the same are out on approval and have not been paid for, and this tag, in accordance with my invention, is secured to the garment in such manner that it cannot, without mutilation, be removed therefrom. The tag will be applied to the garment in such conspicuous position as to deter the wearing of the garment in public while the tag is thereon.

My invention comprises an identifying tag, a pin for securely pinning the same and the garment together and a locking member to be applied to the pin after the pin, tag and garment have been fastened together, for non-removably locking the pin in position, so that neither the pin or tag may be separated from the garment without destroying or mutilating the tag or pin. Garments returned with the tag removed or mutilated will not be received for credit or exchange, and a notice to this effect will be printed on the tag.

The invention will be fully understood from the detailed description hereinafter presented, reference being had to the accompanying drawings, in which:

Figure 1 is a face view of a tag of commercial type locked to a garment, indicated by dotted lines, by means of a non-detachable pin carried by the tag;

Fig. 2 is a transverse section through the same taken on the dotted line 2-2 of Fig. 1,

the garment being shown as partly broken away and in solid lines;

Fig. 3 is an enlarged vertical section through the snap fastener portion of the device taken on the dotted line 3-3 of Fig. 1;

Fig. 4 is a side elevation, partly in section, of the features constituting the locking pin, the head of the snap fastener being illustrated in section and as positioned to be applied to the pin;

Fig. 5 is a top view of the pin, less the fastening head therefor;

Fig. 6 is an enlarged vertical section, partly broken away, through the head end of the pin and the snap fastener parts to be applied thereto, the head for application to the pin being shown as positioned over the shank carried by the pin and provided to receive said head, and

Fig. 7 is a top view of the pin and its shank, the pin being shown partly broken away.

In the drawings 10 designates, diagrammatically, a garment or other piece of material, 11 the merchandise tag to be applied to the garment, and 12 a pin formed from a rod of wire or other suitable material for securing the tag to the garment, said pin having at one end a shank 13 adapted to receive, after the manner of a snap fastener, a head 14 to be pressed home thereon. At the head end of the pin there is a flat metal disk 15 with which the shank 13, which is cylindrical in outline, may be formed, the whole being in one piece of metal; the sides 90 of the cylindrical shank 13 have a suitable number of downwardly and outwardly diverging spring fingers 16, and by preference the shank 13, disk 15, spring fingers 16, and pin 12 are in one integral piece. The shank 95 13 is adapted to receive the hollow head 14, which head has an orifice 17 in its lower side, and said orifice being surrounded by an inturned flange 18. Upon the application of the head 14 to the shank 13 the orifice 17 passes downwardly over said shank and the edges of said orifice force the spring fingers 13 inwardly and thereafter, upon the head 14 reaching its final position, said spring fingers 13 spring outwardly over the flange 100 18 and lock the head 17 in position on said shank, rendering said head non-removable.

The locking pin considered alone therefore

consists of the pin or body portion 12 having the disk 15, shank 13 and spring fingers 16, and the head 14 adapted to be slipped upon and become interlocked with said shank.

- 5 The tag 11 may be of any suitable type, and in the drawings I illustrate a commercial tag of known character having blanks 19 to receive memorandums of the articles to which the tag may be applied, and having also a 10 detachable section 20 provided with corresponding blanks and to constitute a duplicate of the data which may be furnished by the main body of the tag. The tag 11 need not possess the duplicate portion 20, 15 and said tag is not limited to any special memorandums, blanks or the like which may be provided thereon. I prefer to form the tag 11 of good thick paper or cardboard, of the kind commonly employed in mercantile 20 houses, and print on the top of the tag the warning notice, "This article will not be accepted for credit or exchange if tag is removed or mutilated," while below the warning will be provided the blanks 19 to receive 25 memoranda as to the character of the merchandise to which the tag may be applied. The tag 11 is distinctive in several respects, and said tag is formed with a hole 21, and in suitable relation thereto, a plurality of 30 holes 22 the holes 22 being in alinement and adapted to receive the body of the pin 12. The pin is not fastened to the tag in a permanent way until the body of the pin 12 has pinned the tag to the garment by threading 35 the pin through the holes 22 and the garment so as to pin the garment to the tag, as I indicate in Fig. 2, and thereafter I lock the pin to the tag so that the pin cannot be removed therefrom without mutilating the tag, 40 and in carrying out this portion of my invention I insert the shank 13 of the pin through the hole 21 in the tag and thereafter apply the head 14 upon said shanks 13, said head and the disk 15 inclosing opposite face 45 portions of the tag and locking the tag to the pin, or locking the pin and tag together. I do not lock the pin 12 to the tag 11 until after the body of the pin has been utilized in pinning the fabric or garment 10 to the tag, 50 and in consequence, when I thereafter by means of the head 14 lock the pin to the tag so that the pin cannot have any sliding movement with relation to the tag, the pin and tag become locked together and to the 55 fabric or garment 10, it being impossible to remove the tag from the garment without mutilating the tag in order to release the pin from the garment. After the tag has been applied to the garment or fabric 10 and 60 the pin then applied for fastening the tag and fabric together, a portion of the fabric becomes locked upon the pin between two adjacent holes 22 in the tag, as shown in Fig. 2, and hence the fabric cannot be removed 65 from the tag and pin without mutilating

either the fabric or the tag. I prefer to employ three of the holes 22 in the tag 11 since thereby I am enabled to secure a section of the fabric 10 between two of said holes and insert the point of the pin through the 70 remaining hole and protect said point at the back of the tag, as I illustrate in Figs. 1 and 2, the point of the pin thus being concealed and not liable to injure the hand of a person who might be handling the garment. 75 The tag may have the name of the store employing the same printed thereon, and likewise the head 14 of the fastener may be engraved or stamped with any suitable initial, trade-mark or other identifying symbol. 80

I designate my invention as a lock-tag, because with the use thereof the tag and garment of fabric 10 become locked together by the employment of the pin 12, and it will appear obvious that the tag cannot be removed from the garment or fabric without mutilating the tag, or the pin or the fabric. 85

The purpose of this invention is to prevent the too common practice of a person ordering a suit, hat or the like on approval, 90 and after wearing the same, returning the article to the store for credit or exchange. The tag will be placed in such conspicuous location on the garment or other article as to forbid the wearing of the garment in public. 95 Stores are subjected to severe losses by a practice of customers having goods sent home on approval, wearing the same in public, and returning the article for credit or exchange, and as one means for preventing 100 this abuse and breach of confidence, I have provided the present invention, which supplies a tag which will serve as a non-removable badge showing, if the garment is worn in public, that the same is out on approval 105 and has not been paid for.

My invention admits of various modifications, and therefore I do not wish to be limited to the details shown in Figs. 1 to 5 inclusive. In Figs. 6 and 7 I illustrate a 110 modification as to the structure of the shank at the head end of the pin, and Figs. 6 and 7 being illustrative of a modification, I number the pin 30, the shank at one end thereof 31, and the head to be applied on said shank 115 32. The shank 31 is cylindrical and of sheet metal, and is flanged, as at 33, around its base to receive an eye 34 formed on the head of the pin 30, said eye 34 being inclosed by the flanges 33, which will be clamped together against said eye and serve to lock the pin 30 and shank 31 rigidly together. The shank 31 has downwardly diverging spring fingers 35, corresponding with the spring fingers 14 shown in Figs. 3 and 4, and the 120 cap 32 has an orifice 36 and flange 37 surrounding the same corresponding with the orifice 17 and flange 18 of the construction shown in Fig. 4. When the shank 31 is passed through a hole in the tag 11 and the 125 130

head 32 is then pressed home upon the shank 31, the pin and its head portion become fastened to the tag.

The invention admits of further modifications within the scope of the appended claims, since it is to be noted that the essence of the invention, in its broader view, resides in the tag, a pin for securing the tag to a garment or the like and means for so locking the pin in its operative position that neither it or the tag can be removed from the garment without mutilation of one of the other thereof.

What I claim as my invention and desire 15 to secure by Letters-Patent, is—

1. In a device of the character described for use on a garment or the like, a tag, a plain pointed pin threaded through the tag and garment at a plurality of points for pinning the tag onto the garment, and a non-removable locking member securing the head end of said pin and said tag together, thereby enabling that portion of the garment held on the pin to prevent the removal of 25 the pin or tag from the garment.

2. In a device of the character described for use on a garment or the like, a tag, a plain pointed pin for pinning the tag and garment together by passing the pin through 30 a plurality of piercings in the tag and through the material of the garment at two piercings coinciding with adjacent piercings of the tag, and a non-removable locking member applied to said pin for locking the 35 head end of said pin and said tag together and rendering the same non-removable.

3. In a device of the character described for use on a garment or the like, a tag, a plain pointed pin for pinning the tag and 40 garment together and having at one end a shank, and a head for application to said shank, said shank being extended through said tag from one side thereof to receive said head at the other side of the tag, and 45 said shank and head having interlocking parts for rendering said head non-removable from the pin and said tag non-removable from the garment.

4. In a device of the character described 50 for use on a garment or the like, a tag, a

plain pointed pin for pinning the tag and garment together and having at one end a shank, and a head for application to said shank, said tag having a plurality of holes to receive said pin in its application to the 55 garment and a hole to receive from one side of the tag said shank, and said shank being adapted to receive from the other side of the tag said head, and said shank and head having interlocking parts for rendering said 60 head non-removable from the pin and said tag non-removable, without mutilation, from the garment.

5. In a device of the character described for use on a garment or the like, a tag, a plain pointed pin piercing the tag and garment at a plurality of points and pinning the tag and garment together, and a non-removable locking member applied to said pin for rendering the pin and tag, without mutilation, non-removable from the garment.

6. In a device of the character described for use on a garment or the like, a tag, a plain pointed pin piercing the tag and garment at a plurality of points and pinning 75 the tag and garment together, and a non-removable locking member applied to said pin for rendering the pin and tag, without mutilation, non-removable from the garment, said tag being of paper or like material and having three holes to receive said pin, whereby the pin between two of said holes may secure the tag and garment together and have its pointed end inserted through the third hole and concealed at the 80 back of the tag.

7. In a device of the character described for use on a garment or the like, a tag, a plain straight sharp pointed pin pinning the same to the garment through a plurality of piercings, and a non-removable locking member applied to said pin for locking the shank end of said pin and said tag together and thereby rendering the pin and tag, without mutilation, non-removable 95 from the garment.

Signed at New York city, in the county of New York and State of New York, this 22nd day of March, A. D. 1920.

MARCUS B. BEHRMAN.
